UNITED STATES PATENT OFFICE

172,674

COMBINED CLOCK AND CALENDAR

Frederick Lux, Waterbury, Conn., assignor to The Lux Clock Manufacturing Company, Inc., Waterbury, Conn., a corporation of Connecticut

Application August 27, 1953, Serial No. 26,612

Term of patent 7 years

(Cl. D42—7)

To all whom it may concern:

Be it known that I, Frederick Lux, a citizen of the United States, residing in Waterbury, in the county of New Haven and State of Connecticut, have invented a new, original, and ornamental Design for a Combined Clock and Calendar, of which the following is a specification, reference being had to the accompanying drawing, forming part thereof, in which

Fig. 1 is a front elevational view of a design for a combined clock and calendar embodying my invention;

Fig. 2 is a side elevational view thereof;

Fig. 3 is a side elevational view looking from the opposite side to that shown in Fig. 2; and

Fig. 4 is a top plan view.

I claim:

The ornamental design for a combined clock and calendar as shown.
